BRICK FINISHING MACHINE

Walter C. Wandroik, Northbrook, and Henry Krisor, Morton Grove, Ill.

Application June 22, 1939, Serial No. 280,638

1 Claim. (Cl. 25—1)

This invention relates to a machine for treating or converting a common clay brick column while in a plastic state, into rough texture brick of any desired, preferably colored, semi-face brick.

A prime object is to provide a machine in the nature of an attachment to existing machinery so that the latter may still be used and our improvements employed in addition thereto, at minimum expense.

It is further aimed to provide a construction wherein the brick may be produced inexpensively and expeditiously, and treated according to our invention, by means coacting with the brick while being conveyed from the die.

The more specific objects and advantages will become apparent from a consideration of the description following taken in connection with the accompanying drawings illustrating an operative embodiment.

In said drawings:

Figures 1 and 2 are fragmentary side elevations selectively showing the machine, adapted to be joined at the lines A—A shown on each;

Figures 3 and 4 are plan views, collectively showing the machine, fragmentarily, being adapted for joining at the lines A—A shown on each;

Figure 5 is a vertical transverse sectional view taken on the plane of line 5—5 of Figure 1;

Figure 6 is a transverse detail section showing the discharge portion of one of the hoppers for coloring material;

Figure 7 is a detail elevation of one of the cutting wires, and

Figure 8 is a detail section taken on the plane of line 8—8 of Figure 1.

Referring specifically to the drawings wherein like reference characters designate like or similar parts, 10 designates the die of a brick machine, through which the brick clay, in a plastic state, is expressed in two spaced apart, similar columns 11, rectangular in cross section.

Said columns 11 are received by and carried from the machine by a suitable endless conveyor 12, at the upper run of the latter. Such columns 11 as conveyed forwardly, are transferred, through the aid of a bridge 13, to the upper run of a second endless conveyor 14, preferably traveling somewhat faster than the endless conveyor 12. Such conveyors are mounted by a conventional framework 15 and associated parts.

A cutting or severing wheel 16 is rotatably mounted at 17 on the framework 15 and it has any desired number of radial arms 18 joined by

cutter wires or the like 19, disposed parallel to the axis 17.

The parts described are conventional in the art and it will be realized that as the columns 11 are transferred from the conveyor 12 to the conveyor 14, they are penetrated by the wires 19, thus cutting off bricks 11a which are spaced apart on the conveyor 14, due to the difference in speed of travel of the two conveyors.

10 In accordance with the invention, a supplemental base or frame is provided at 21 over the conveyor 12, supported by the framework 15 and consisting primarily of parallel channel beams 22. A lever 23 is pivoted by means of a rod 24 in bearings 25 on the beams 22 and at the opposite end, has a head 26 carrying any suitable number of roughening or scratching members wires or the like 27 as well shown in Figure 5, which are adapted to roughen or groove one 20 surface of the brick columns 11 as the latter are conveyed past the same. Preferably four of the scratching elements are provided for each column, although the number may be varied as desired. A plate 28 spans the beams 22 and is 25 fastened thereto, having a bolt 29 screw threaded thereto. Another plate 30, crosses the lever 23, being fastened thereto and having an opening through which the bolt 29 loosely passes. An expansive spring 31 surrounds bolt 29, abutting plate 30 and the head of the bolt at opposite ends, thereby yieldingly maintaining the scratching elements 27 in lowermost and operative position. The depth of scratching or roughening is variable 30 through the adjustment of screw 29, as will be understood.

At each side of the machine, adjacent the roughening elements 27, guide rollers are provided for the columns 11 as at 32, the same preferably having their periphery fleece lined. Such 40 rollers operate in openings 33 of beams 22 and they have vertical shafts 34 journaled in a frame 35, pivoted by a shaft 36 in bearings 37 at the outer side of the beams 22 and positioned through the coaction of a screw 38 passing through a plate 45 39, such screws preferably having springs associated with them, so that the pressure of the rollers 32 will be yieldable.

After passing the scratching members 27, the columns 11 pass under a hopper 40 which 50 contains coloring material preferably in granular or sand form. This material falls by gravity from the hopper 40 onto the grooved surfaces of the columns 11 (Figure 6) under control of a valve or gate 35', through an outlet 36', the position 55 of such gate or valve being adjustable or variable

by latch means at 37' so that the supply may be properly regulated. Rollers 38' are supplied at the sides of the beams 22, operating in openings 39' thereof, and being journaled by means of vertical shafts 40' in bearings 41 fastened to the outer sides of the beams 22. The granular material or sand supplied by the hopper 40 is in such quantity that it not only covers the grooved surfaces of the columns 11 but it also overflows and is sufficient to cover all four vertical surfaces of the columns exposed at such point. The rollers 38' serve to press the granular material or sand, which may be of any desired color, into the columns. Since such rollers 38' are tapered as shown, and smaller at their upper ends, they will retain some of the granular material between the same and the outer sides of the columns, aiding in the reception of the latter and the pressing thereof into the columns.

Beyond the hopper 40 and rollers 38', the columns are engaged at their tops or grooved surfaces at their outer sides by surfacing rollers 42 which will restore the faces on the columns engaged to their original dimensions, primarily removing any excess roughness and leaving the columns in condition for burning as a rough texture, semi-face brick. Such rollers 42, having shafts 43 journaled in frames 44, pivoted at 45 on the beams and they are spring urged as at 46, into engagement with the columns, like the frames 23 and 35. The rollers 42 at the sides, pass through openings 47 in the beams.

Beyond the rollers 42, the advancing columns 11, are engaged by the severing means 16 so that bricks 11a are produced and are conveyed in spaced relation by the conveyor 14, such bricks having their upper surfaces and longitudinal vertical surfaces treated in accordance with the invention. Over the conveyor 14, a hopper 43 is mounted to contain the same granular coloring material or sand as the hopper 40 which it discharges under appropriate regulation or control into the outlet duct 48 of a blower 50 in which a fan 51 is operated from an electric motor or the equivalent 52, as through the medium of a belt drive 53. The parts mentioned are supported by a framework 54, fastened by brackets 55 to the framework 15. Duct 48 has an outlet nozzle 56 of a size wider and longer than the distances between the ends of the bricks 11a so that the coloring material as shown in Figure 2, will

be effectively blown in such quantity and area as to cover the ends of the bricks 11a. In addition, attention is called to the fact that the material blown through the nozzle 56 has the action of a sand blast which not only roughens the ends of the bricks 11a but all of the surfaces exposed, that is, all except the lower surfaces engaged with the conveyor 14. Following this treatment, the bricks 11a are removed from the conveyor 14 and directed in the manner conventional in the art.

The elements or wires 19 are equipped with barbs in the form of rings or enlargements at 19a, preferably being lined with the scratch members or pins 27 so that simultaneously with the severing of the bricks 11a, their ends will be grooved, roughened or the like like the upper surfaces of the bricks, the grooves on such ends being aligned and similar in number to the grooves on the upper surfaces.

The peripheries of rollers 32 and 38 are preferably fleece lined while those of rollers 42 are hard or metallic, for instance of brass.

Various changes may be resorted to provided they fall within the spirit and scope of the invention.

We claim as our invention:

Apparatus of the class described comprising a pair of parallel, horizontally disposed beams between which a column of plastic material is adapted to pass, a substantially horizontally disposed lever positioned at the tops of the beams, means securing said lever to the tops of the beams for pivotal movement, roughening elements carried by the lever adjacent one end thereof and operable in the space between the beams to engage the column, a plate disposed across the top of the beams between the fulcrum of the lever and said elements, a screw passing loosely through the lever and threaded to the plate, and a spring surrounding the screw and bearing on the upper surface of the lever for urging the elements downwardly, said beams having openings therethrough, levers pivoted to the outer sides of the beams, surfacing rollers carried by the second-mentioned levers and positioned in the openings for engagement with the column, and spring means associated with the second-mentioned levers for urging said rollers into engagement with said column.
